GOLF PUTTER HEAD

David L. Phares, 2330 W. Whitton,
Phoenix, Ariz. 85015

Filed Oct. 3, 1969, Ser. No. 19,400

Term of patent 14 years

Int. Cl. D21—02

U.S. Cl. D34—5

FIG. 2

FIG. 3

FIG. 4

FIG. 1

FIG. 1 is an isometric view of a golf putter head showing top, front, and left surfaces;

FIG. 2 is a front view thereof;

FIG. 3 is a top view thereof; and

FIG. 4 is an isometric view showing top, front, and right surfaces thereof.

I claim:

The ornamental design for a golf putter head, as shown.
